[57] **CLAIM**

The ornamental design for a collapsible headset, as shown.

DESCRIPTION

FIG. 1 is a front elevational view of the collapsible headset of the present invention showing one side of the headset in collapsed condition and the other side extended;

FIG. 2 is an end elevational view thereof showing the extended end of the collapsible headset;

FIG. 3 is an end elevational view thereof taken from the collapsed end of the collapsible headset;

FIG. 4 is a top plan view thereof; and

FIG. 5 is a bottom plan view thereof.

*FIG. 1**FIG. 2*

FIG. 4

FIG. 3

FIG. 5
